UNITED STATES PATENT OFFICE.

FLORAIN J. SHOOK, OF AKRON, OHIO, ASSIGNOR TO THE B. F. GOODRICH COMPANY, OF NEW YORK, N. Y., A CORPORATION OF NEW YORK.

ATTACHMENT DEVICE.

Application filed October 20, 1923. Serial No. 669,743.

This invention relates to devices for attaching articles to supports such as the wall of a container in which the article is packed, and is primarily designed for use in connection with a rubber article, such as a flush tank valve, having molded therein a metallic, internally threaded spud. Such articles are frequently damaged by coming in contact with the walls of their containers during shipment or while kept in stock by the dealer, their own weight being sufficient to distort them from the true form required for their proper functioning. Heretofore various expedients have been employed for supporting such articles within the shipping containers, a common expedient being to support the valve with its circumferential rib, with which such valves are commonly formed, resting upon the top of a cardboard cylinder into which the valve extends, but in this practice displacement frequently occurs. Another practice heretofore employed consists in supporting a rectangular piece of cardboard in a horizontal position near the top of the container, passing a screw through the central part of the cardboard and threading said screw into the metallic spud of the valve. Thus the soft rubber valve is firmly suspended, but this practice requires considerable time for mounting the screw in the spud, and the screws are a matter of substantial expense.

My chief object is to provide an attaching means which will be positive in action and may be quickly and securely attached to the valve. A further object is economy in the manufacture of the attaching device.

Of the accompanying drawings:

Fig. 1 is a perspective view of a preferred form of my improved attachment device.

Fig. 2 is an elevation, partly in section, of a cardboard support and a flush tank valve attached thereto by my device.

Referring to the drawings, the attachment device preferably consists of a length of soft wire so bent as to provide an annular base 10, an arm 11 extending from said base radially to its axis, and an expansion head or cam-latch portion comprising a reach of wire 12 extending axially from and in continuation of said arm, and terminating in a hooked portion 13 formed by bending the wire reversely upon itself and then outwardly from the axial portion 12,

to form a yielding projection having an outwardly directed corner 14.

The support for the bent wire device comprises a cardboard easel or U-shaped standard of such dimensions as to fit into the shipping box or container, said standard comprising a top portion 15 provided with supporting legs 16 and formed with an aperture 17 at its center. In assembling the valve, the bent wire device, and the standard, as shown in Fig. 2, the axially disposed, hooked portion 13 of said device is passed through the opening 17 of the standard and is then pressed into the internally threaded spud 18 of the valve 19. Due to the resiliency of the wire forming the portion 13, the projection upon which the corner 14 is formed yields so as to permit the expansion head to enter the spud 18, without being screwed thereinto, but the projection or corner 14, entering between the threads, in the manner of a cam latch, prevents removal of the device from the spud by direct pull, although it readily may be removed by a counter-clockwise relative rotation or unscrewing of the valve 19.

The valve being thus attached by its spud, it cannot elsewhere contact with the legs of the standard or with the walls of its container except at its circumferential rib, 20, whatever position the container may be given, and even though the bulb fits snugly within the standard. Damage of the lower, hemispherical, sealing portion of the valve is thus avoided. If clearance be provided between the standard and the valve, the latter may be supported by its spud, without any other point of contact, the spud then preferably being forced further onto the bent wire device and against the top portion 15 of the standard, so as to provide a firm connection such as will prevent swinging of the valve.

Modifications may be resorted to within the scope of my invention, and I do not wholly limit my claims to the exact construction shown.

I claim:

1. An attachment device comprising a part adapted to engage one of the members to be attached and a hooked wire portion adapted to be sprung into a female threaded member by axial thrust, the end of said wire portion being formed with a corner

adapted to have a cam-latch action with relation to the threads of said female threaded member.

2. In combination with an article provided with a female thread, an apertured support for the same, and an attachment member comprising a base portion engaging said support about the aperture thereof, and a bent wire portion extending laterally from said base portion, through said aperture, and engaging the threads of said article in such manner as to enable the article to be locked in contact with the support by an inward axial thrust of said attachment member.

3. An attachment device comprising a unitary wire bent to form a support-engaging portion and a cam-latch portion extending therefrom, the wire of said cam-latch portion being reversely bent and terminating in an outwardly projecting portion having a corner adapted to interlock with the thread of a female threaded member against a reversal of axial movement when said cam-latch portion is sprung, by axial thrust, into said female threaded member. 20 25

In witness whereof I have hereunto set my hand this 12th day of October, 1923.

FLORAIN J. SHOOK.
